UNITED STATES PATENT OFFICE

144,414

DESIGN FOR A TOY FIGURE

Alfred G. Promer, Detroit, Mich.

Application May 12, 1945, Serial No. 119,521

Term of patent 3½ years

(Cl. D34—15)

To all whom it may concern:

Be it known that I, Alfred G. Promer, a citizen of the United States of America, residing at Detroit, in the county of Wayne, State of Michigan, have invented a new, original, and ornamental Design for a Toy Figure, of which the following is a specification, reference being had to the accompanying drawing, forming a part thereof, wherein:

Fig. 2 is a side elevational view of the toy figure shown in Fig. 1 with the handle partially broken away for convenience in illustration.

I claim:

The ornamental design for a toy figure, as shown and described.

ALFRED G. PROMER.
